UNITED STATES PATENT OFFICE.

CHARLES A. ALLEN, JR., OF LA GRANGE, ILLINOIS.

DESIGN FOR A COFFEE-PERCOLATOR.

47,681.

Specification for Design. Patented Aug. 10, 1915.

Application filed May 13, 1915. Serial No. 27,936. Term of patent 14 years.

To all whom it may concern:

Be it known that I, CHARLES A. ALLEN, Jr., a citizen of the United States, residing at La Grange, in the county of Cook and State of Illinois, have invented a new, original, and ornamental Design for Coffee-Percolators, of which the following is a specification, reference being had to the accompanying drawing, forming part thereof.

The drawing is a perspective view of my coffee percolator.

What I claim is:

The ornamental design for a coffee percolator, as shown.

CHARLES A. ALLEN, JR.

Witnesses:

STANLEY W. COOK,
MARY F. ALLEN.
